United States Patent Office.

L. W. TURNER, OF, YALESVILLE, CONNECTICUT, ASSIGNOR TO HIMSELF
AND G. S. WILCOX, OF SAME PLACE.

Letters Patent No. 63,187, dated March 26, 1867.

IMPROVED WEATHER STRIP.

The Schedule referred to in these Letters Patent and making part of the same.

TO ALL WHOM IT MAY CONCERN:

Be it known that I, L. W. TURNER, of Yalesville, in the county of New Haven, and State of Connecticut, have invented a new improvement in Weather-Strip; and I do hereby declare the following, when taken in connection with the accompanying drawings, and the letters of reference marked thereon, to be a full, clear, and exact description of the same, and which said drawings constitute part of this specification, and represent, in—

Figure 1, a side view of a door, a portion of the bottom rail broken away to show the weather strip; and Figures 2 and 3, detached views.

This invention is designed to be inserted in a groove in the bottom rail of a door, and to operate so that, when the door is closed, the space between the door and threshold will be closed; and consists in the peculiar construction of the weather strip, whereby it will conform to the surface of the threshold, whether straight or worn away.

To enable others to construct and use my improvement, I will proceed to describe the same as illustrated in the accompanying drawings.

A B are two sections of the strip, divided at or near the centre at *a*, and hinged together by a cap, *c*, passing over the two sections, and pivoted at *d*, so that, when the two sections lie in a straight line, as in fig. 1, the under surface of the cap bears upon both sections, so that, when a lever, *D*, pivoted at *e*, is depressed by one arm *f* coming in contact with the jamb of the door, the other arm *h*, resting on the cap *c*, depresses both sections of the strip; and when relieved from such pressure a spring, *F*, or an equivalent therefor, attached to the cap, raises both sections of the strip; and when the threshold has been worn away, so as to be lower in the middle than at the two ends, then an increased pressure will force down the centre of the strip, as seen in fig. 2, the two ends being held up by the uneven surface of the threshold.

In order to cause the strip to conform perfectly to any unevenness of the threshold, I prefer to form the two sections so as to enclose a strip of India rubber, or similar flexible material, and so as to leave a portion of the flexible material projecting below the edge of the strip, as denoted in heavy black, fig. 3.

I do not wish to be understood as claiming an India-rubber or elastic edge to the strip, as such, I am aware, is not new.

Having thus fully described my invention, what I claim as new and useful, and desire to secure by Letters Patent, is—

The combination of the lever *D* with the two sections *A B*, spring *E*, when the two sections are arranged so as to be operated simultaneously, substantially in the manner described.

L. W. TURNER.
